ELECTRIC VIBRATOR

Adolf P. C. Schramm, New York, N. Y.

Application June 20, 1933, Serial No. 676,611

7 Claims. (Cl. 128—49)

This invention is a novel electric vibrator such as is adapted for massage purposes, although the features of improvement would be available for other practical purposes such as treatment or mixing of liquids, or use in the laboratory or otherwise for grinding, cutting, polishing or other treatments of solids, such as a vibratory razor.

The general object of the invention is to provide an electric vibrator operated by a motor of the type having an oscillating shaft, permitting a simple construction in that a plain iron armature without winding may be employed, with a restoring spring opposing the field magnet. Such a motor may be operated by intermittent or alternating current and in the latter case the vibrations may be synchronous with the frequency of current alternation, as 60 cycles per second, the vibrator delivering an oscillating movement which is powerful although scarcely perceptible to the eye.

A special object is to provide for the varying of the power or action of the vibrator, for massage or other purposes, preferably by adjustment of the spring which operates on the armature. Another object is to provide a structure and arrangement of parts whereby the user of the vibrator is protected from possible short circuit, all accessible parts being insulated from stray currents. Another object is to provide a control arrangement whereby the picking up and the gripping of the handle of the vibrator effects the closing of the circuits and the operation of the apparatus, the laying down of the vibrator causing its stoppage.

Other objects include providing, in the case of massage, of special applicators, to be subjected to the oscillating motion and to deliver effective massage action.

Other and further objects and advantages will be explained in the hereinafter following description of an illustrative embodiment of the invention or will be understood to those conversant with the art.

In the accompanying drawing Figure 1 is what may be termed a front view or elevation of an electric massage vibrator embodying the present invention, with a special type of applicator applied thereto.

Fig. 2 is a right elevation of the apparatus of Fig. 1, the handle broken away.

Fig. 3 is a rear elevation of the interior parts, the housing being shown in section and broken away in parts.

Fig. 4 is a left elevation with half of the housing removed, and certain parts in section.

Fig. 5 is a detail cross section showing the preferred construction of each of the elements of the ball type of applicator shown in Figs. 1, 2 and 4; and Fig. 6 is a right elevation thereof.

Fig. 7 is a bottom view of the button type of applicator shown in Fig. 8; and Fig. 8 is a central section thereof.

Fig. 9 is a central section of a comb type of applicator, adapted to be mounted on the form shown in Fig. 8.

Fig. 10 is a sectional and Fig. 11 a perspective view of a detail of construction of the fixed parts of the apparatus.

Fig. 12 is a rear elevation partly in section of a detail of the mounting and adjustment of the armature spring.

Figs. 13 and 14 are diagrams of the action showing respectively a strong and a weak adjustment of action.

Referring first to Figs. 3 and 4 and the diagrams Figs. 13 and 14, a laminated armature 20 is shown mounted on an oscillating shaft 21, the poles of the armature being arranged to oscillate between the poles 22 of a laminated magnet having windings 23 at the poles or elsewhere and a magnet body 24 of ring, octagon or other suitable shape.

A front bearing bracket 26 in the nature of a bridge extends horizontally across from one side to the other of the magnet body and at its center carries a bearing 27 for one end of the shaft 21. Extending down from the bridge or bracket 26 are a pair of spaced apart ears 28 perforated for the reception of a bolt by which the housing, to be referred to, is attached to the enclosed apparatus. At its ends the bridge is formed with a pair of small tabs 29 straddling an insulating washer 30 as shown in detail in Figs. 10 and 11. Through these parts and another insulating washer extends a bolt 31 which passes also through the body of the magnet, making a tight fit therewith, and issuing at the rear side where are further insulating washers and a nut 32 by which the front and rear bearing brackets are rigidly attached to the magnet. The tabs center the washers and thus center the bolt which is thus kept from metallic contact with the front and rear bridges or bearing brackets.

A rear bracket or bridge 36 is bent or looped rearwardly so that the bearing 37 thereon for the shaft 21 is spaced well to the rear, that is at the left side of Fig. 4. The bridge 36 has a pair of upstanding ears 38 perforated for an attaching bolt and at its ends has tabs 39 straddling an insulating washer 40. By the described arrange-

ment of the two bridge brackets 26 and 36 and the washers 30 and 40 the securing bolt 31 is maintained spaced so as to be free of metallic contact with the two bearing brackets. The rear bracket 36 has a bent downward extension 41 having a horizontal slot as seen in Fig. 3 and horizontal ears 42 perforated to receive an adjusting shaft. The mountings for the oscillating motor shaft 21 have thus been completely described.

10 The armature 20 is to be resiliently held in or restored to its neutral position indicated by the diagram axis *a* or *a'* in Figs. 13 and 14. For this purpose the armature has an outstanding stud 45 at one side receiving an eye on the free end 15 of a restoring spring 46, which is preferably a helical spring surrounding the shaft 21. The other or anchored end of the spring extends downwardly through a swivelling head 47, shown in detail in Fig. 12, this head being rotary within 20 a sliding carriage 48, the threaded shank 49 of which is slidable horizontally, guided in the slot of the bracket extension 41. A threaded shaft 50 passes through and is threaded in the shank 49, the shaft being rotary in the ears 42 of the extension 25 and being there confined by an enlargement or head at each end. The right end of the threaded shaft 50 is provided with a thumb nut or adjuster 51 extending through to the outside of the housing to be described, and the inner side 30 of this knurled thumb piece is engaged by a spring tooth or click 52 which securely holds the thumb piece against accidental displacement.

The entire mechanism thus described is preferably enclosed in a non-metallic housing which 35 is shown as composed of a right half 55 and a left half 56 interlocking with each other, these having ventilating slots to minimize overheating. They may be composed of a strong composition material such as bakelite or fiber, and each half 40 has an extension 55^a or 56^a which match to form a convenient handle 57.

The two halves of the housing and the enclosed mechanism are all interconnected by an upper bolt 58 and a lower bolt 59. The right half has a 45 pair of threaded seats 60 one for each of the bolts, one of them appearing in Fig. 3, while the left half has a pair of receiving sleeves 61 for the respective bolts, one such sleeve appearing in Fig. 3. The handle part 55^a has a threaded seat 62 and 50 the complementary handle part a sleeve, not shown, to receive a securing bolt 64. When tightened in place the three bolts 58, 59 and 64 hold the entirety in rigid relation.

The electric arrangements and circuits may be 55 as follows. A double wire line 67 passes through an aperture in the lower end of the handle, a knot 68 preventing pull thereon. Within the handle the separate wires are split. A single wire 69 passes from this point upwardly to the upper magnet coil 23, which in turn is connected by a 60 single wire 70 with the lower coil 23, this in turn being connected by a single wire 71 with a spring contact member 72 adapted to be thrust at will into contact with a second contact member or 65 spring 73, to which the other line wire is directly connected. The circuit is thus normally open. The two contact members are mounted in a slit lug 74 in the left handle part, and a pivoted lever 75 projecting beyond the handle is so arranged 70 that gripping the handle deflects the spring 72 and closes its contact with spring 73. By this arrangement the vibrator is put into operation at will, and on laying it down the contact automatically opens.

75 Various forms of operating devices or appli-

cators are attachable to or operable from the oscillating shaft 21. Devices are illustrated in the nature of massage implements, but as stated, other devices might be actuated from the oscillating shaft. The shaft is shown with a threaded end 5 76 on which the threaded head or shank 77 of the applicator or other device is attached, with a wing nut 78 to lock it in place. The head 77 may carry massaging elements either axial or offset. Thus in Figs. 1, 2 and 4 are shown a series 10 of three or two rounded or ball shape applicator elements. Each of these has a shank 79 attached by driving fit eccentrically in the head, and on each shank is a ball 80, which in these cases is 15 preferably rotatable on its shank and also preferably is arranged for yielding along its shank, being made with a recess for this purpose. Figs. 5 and 6 show suitable details, there being a screw sleeve 81 attached within the non-metallic applicator element 80, the shank 79 having a round interior head 82, with a spring 83 compressed between the shank head and the base of the recess. The ball may be composed of bakelite, fiber or the like and may yield progressively along its shank, giving a graded action according to the 20 pressure applied. The several balls act in cooperation, forming a series which oscillate or planetate along small arcs around the main shaft 21 as 25 an axis, this arrangement being very effective for certain muscular treatments.

A button type applicator is shown in Figs. 7 and 8 where the shank 85 is threaded to be mounted upon the main shaft 21 and carries the button applicator 86 which in this case is not to be rotary on its shank since the shank must 35 transmit oscillatory movements to the button. As before the non-metallic button has a threaded sleeve 87 through which the shank passes, the shank having a square head 88 slidably in the square recess 89 against the resistance of compression spring 90.

For scalp treatment the comb-like attachment 91 of Fig. 9 may be used, this having a circular series of teeth 92 and the entirety being applicable for example to the button applicator 86 of 45 Figs. 7 and 8. The ends of the teeth contacting the scalp will have oscillating motions along the line of their own circle. Various other applicators operable by oscillating motion will suggest themselves.

The subject matter of Figs. 7, 8 and 9 thus described is not specifically herein claimed, but is made the subject of claim in copending application Serial No. 714,896, filed March 10, 1934.

The cooperation action of the magnet and 55 armature is diagrammatically shown in Figs. 13 and 14, these two figures showing substantially the extreme adjustments of the action by the thumb piece 51. Fig. 3 shows an intermediate adjustment, the carriage 48 having been slid 60 part way from one end toward the center of the feed screw 50. It will be noted that as the vibrator is held naturally in the hand, the thumb piece is readily accessible to the thumb and may easily be turned in either direction to vary the 65 adjustment and the power while the massage operations are in progress. This is of considerable advantage, saving time, facilitating the desired adjustment and economizing current.

The adjustment of Fig. 13 may be considered 70 the strong adjustment. The transverse axis *a* of the armature, in its neutral position, is swung away to a maximum degree from the center line or axis of the poles of the magnet. In this adjustment, at rest, the armature stands at the 75

position *a*. When the handle is gripped to press the switch lever *75* and close the circuit the magnet becomes alternately energized, and the armature jumps from its neutral position to a position nearer to the magnet axis, where it undergoes short oscillatory vibrations, for example between the radial lines *b* and *c*. The action is substantially that as the magnetism approaches maximum in each cycle the armature is pulled bodily from *b* toward *c*, the pull continuing until after the magnetism has passed maximum and is reducing toward zero, until a point is reached where the spring, meanwhile put under tension or strain by the movement of the armature, overcomes the weakening strength of the magnet. About this instant the armature will start its reverse movement from position *c* back toward position *b* while the magnet strength decreases to the zero point and thereupon increases with reverse polarity, until, by the time the armature has been pulled back by its spring as far as position *b* the increasing strength of the magnet has overcome the pull of the spring. In a sense the armature is suspended in an intermediate position under short vibration, the magnet intermittently tending to pull it into line with the magnet poles, while the spring is constantly tending to pull it back to neutral position *a*; the armature never reaching either the magnet pole position or the neutral position, until indeed the current is discontinued when the spring restores the armature to its neutral position *a*.

In the diagrams it is not intended to illustrate the exact positions and amplitudes of movements. In practise the actual movement may be quite small, so as to be scarcely perceptible to the vision, and yet quite powerful so as to be extremely perceptible to the parts being massaged. In Fig. 13 the spring is under greater tension than Fig. 14 and the power delivered is greater. In the adjustment of Fig. 14 the amplitude and power are less. The change of adjustment may be considered as the shifting of the neutral axis *a* or *a'* between the extreme and intermediate positions. Fig. 14 shows the weak adjustment, with an oscillation between radii *b'* and *c'*, of small amplitude and energy. This change of adjustment of action is effected by a suitable change in the restoring spring, which preferably, as shown, is a mere shift of the spring by adjusting rotarily the position of its anchored end.

The type of applicator shown in Figs. 1, 2 and 4 is of certain special value for muscular massage, for example in treating the arm muscles. Each ball *80* is freely rotatable on its own shank *79*, but both, or all three, of the balls cooperatively move about the general axis, during which each of them may roll slightly on the skin, with a short oscillatory planetation. In addition to the rolling massage effect described the balls *80* are subject to yielding along their shanks, as explained in connection with Fig. 5. The result is that when light application pressure is increased the rolling balls may slide relatively inward along their shanks, which not merely increases the tension of the spring *83* and the massage pressure upon the flesh, but causes the relative approach of the two or the three balls so as to give a gentle pinching or gathering action upon the flesh. This type of applicator therefore affords simultaneous pressure, vibration, rolling motion, and gathering or kneading of the muscles, according to the manual pressure applied to the operation.

The button type applicator of Figs. 7 and 8 is on different principles, although possessing the yielding action due to its spring *90*. The spring may for example be normally under substantially zero compression, so that the applicator may be operated with very gentle action, the spring yielding with increase of pressure and thus affording a progressively increasing, but always resilient massaging pressure. For facial treatments this is of great advantage. The applicator *86* is not rotary upon its shank *85*, but due to its square recess *89* and head *88* it partakes of the oscillation of the motor shaft, thus delivering a combination of pressure and oscillatory vibration of the muscles in the plane of the operating surface of the applicator, which is shown preferably flat, but obviously might be somewhat curved or otherwise contoured.

The vibrator hereof is safe, electrically speaking, and the user is protected from possible contact with the charged parts and from stray currents due to possible looseness or breakage of connections. The housing is non-metallic and no metallic parts are exposed other than the end of the armature shaft and the applicator head or shank connected therewith. The armature and its shaft are effectively insulated from the magnet and its coils. The bolts *31* by which the bridge pieces *26* and *36* are attached to the magnet are insulated not from the magnet but from the bridge pieces. The non-metallic switch lever *75* protects the user from possible contact with the metallic switch members *72* and *73*.

The claims of this patent are directed to the disclosed electric vibrator, while the particular forms of applicators hereinabove described are made the subject of divisional application, see application Number 714,896, filed March 10, 1934.

The following claims of invention are hereby made:

1. An electric vibrator comprising a shaft mounted to oscillate about an axis longitudinal to its length and adapted to carry an implement or applicator in position intersected by such axis, a field magnet consisting of an electromagnet energized by alternating current, an armature carried by said shaft in magnetic relation to said magnet, a resilient means or spring connected with and tending to hold the shaft at a normal idle position wherein the armature is out of magnetic alignment with the magnet and said spring cooperating with the magnet for oscillating the armature and shaft, and adjusting means for changing the relation of the spring to the armature and thereby effecting variations of the strength or amplitude of oscillation of the shaft and applicator.

2. An alternating current electric vibrator comprising a shaft mounted to oscillate about an axis longitudinal to its length and adapted to carry an implement or applicator in position intersected by such axis, a windingless armature on said shaft, a field magnet consisting of an electro-magnet energized by alternating current, with a spring tending to hold the shaft at a normal idle position wherein the armature is out of magnetic alignment with the magnet, and said spring cooperating with the magnet for oscillating the armature and shaft, and means for adjusting the spring for changing its position and thereby the normal position of the armature for effecting variations of the strength or amplitude of oscillation of the shaft and implement carried thereon.

3. A vibrator as in claim 2 and wherein the spring has one part anchored and the adjustment of oscillation is by shifting the anchored part of the spring thereby to vary the normal position and the range of oscillation of the shaft.
4. A portable electric massage vibrator comprising a shaft mounted to oscillate about an axis longitudinal to its length and adapted to carry an implement or applicator in position intersected by such axis, an armature on said shaft, and an A. C. field magnet; with a spring tending to hold the shaft and armature at a normal idle position and cooperating with the magnet for oscillating the armature and shaft, and adjusting means for shifting the normal position of the spring and thereby effecting variations of the strength or amplitude of oscillation of the armature and shaft thereby to adjust the strength of action of the applicator; the spring being a coil 15 spring surrounding the shaft with one end attached to the shaft or armature and the other end attached to a carriage, the adjusting means being arranged to shift the position of the carriage.
5. An electric vibrator comprising an armature shaft mounted to oscillate about an axis longitudinal to its length and adapted to carry an implement or applicator in position intersected by such axis, an armature thereon, and a field magnet energized by alternating current for oscillating the armature and shaft, a spring tending to hold the shaft at a normal idle position, said spring passing helically around the shaft, with one end attached to the shaft, a carriage to which

the other end of the spring is attached, and adjustable means to shift the carriage in a manner to shift the attached end of the spring and thus vary the action of the spring.

6. An electric vibrator as in claim 5 and wherein the adjustable means to shift the carriage and thereby vary the action of the spring comprises a threaded shaft engaging the carriage and a thumb piece on the shaft exteriorly accessible for turning it.

7. In a portable massage instrument, in combination, an A. C. magnet and a windingless armature, an oscillating shaft having fixed bearings and carrying the armature in a position to oscillate concentrically to the axis of the shaft, and the magnet having a fixed position with its pole or poles radially outwards of the armature pole or poles, such that oscillation of the armature changes the angular relation of the armature poles and magnet poles without contact, each 15 armature pole having a normal position with its magnetic center out of alignment between the magnet pole and shaft axis; and a spring connected to the armature to hold it resiliently in such normal position and having means for initially adjusting the spring to determine the normal position of the armature and thereby the manner of oscillation of the shaft; and a massage applicator mounted at the end of such oscillatory shaft and with the shaft axis passing substantially centrally through the applicator, whereby the applicator applies a reversely twisting movement to the parts contacted by it.

ADOLF P. C. SCHRAMM.
